NOZZLE USED FOR SANDBLASTING PURPOSES

Charles Davies Spenle, Northenden, England

Application January 6, 1942, Serial No. 425,722
In Great Britain January 8, 1941

5 Claims. (Cl. 51—11)

This invention relates to improvements in and connected with discharge nozzles used with sand blasting apparatus for sand blasting purposes, such as the sand-blasting of castings, and other articles or structures, for cleaning and scarifying purposes, or for sand blasting etched or other surfaces as is known.

The discharge nozzles attached to the flexible or other pipes and which discharge the steel grit, sand or abrasive particles are subjected to great wear. For such reason they rapidly become inefficient and have to be discarded because the nozzles become inefficient or useless.

According to this invention there is to be used a nozzle or chuck or holder which is devised or constructed to receive and hold combining renewable inter-engaging or abutting or re-conditioned elements so that a built-up liner or lining components inter-connecting or contacting or adaptable or adjustable one to another can be introduced and secured in the nozzle or chuck when serious wear of such elements has taken place.

Means are used to clamp and where necessary permit adjustment of the renewable or introducible and combining lining elements.

Accordingly under this invention use is made of a nozzle body or chuck of appropriate construction for attaching to the pipe line and for handling and fashioned to receive and support the renewable or inter-changeable or re-conditioned liner elements of cast-iron, steel, tungsten-carbide, or other metal or alloy; which elements are fashioned to combine or produce the renewable or interchangeable liner structure to be secured in the chuck or nozzle body.

The invention is hereafter fully explained and described, reference being made to the accompanying drawings which show several constructions.

In the said drawings:

Fig. 1 shows an end elevation of a nozzle or chuck at the inlet end and with the combining renewable hard wearing elements situated at the inlet end.

Fig. 2 is a separate view of one of the combining renewable elements of which six are seen in position at Fig. 1.

Fig. 3 shows an end view of Fig. 2.

Fig. 4 is a longitudinal section on the line 4—4 50 in Fig. 1.

Fig. 5 shows a view of the structure looking upwards from the bottom of Fig. 4.

Fig. 6 is a separate view of one of the renewable and interchangeable hard wearing liner ele-

ments (capable of being re-conditioned) seen in Figs. 4 and 5.

Fig. 7 is a plan at the inlet end and shows a slot type of nozzle with renewable and changeable combining hard wearing liner elements.

Fig. 8 shows a section on the line 8—8 of Fig. 7.

Fig. 9 is a side elevation of Fig. 7.

Fig. 10 shows an end view looking towards the outlet.

Fig. 11 shows an assembly of wear resisting re-faceable and renewable liner elements of modified cross-section.

According to this invention and with reference to Figs. 1 to 6 there is used a nozzle body or chuck which is of appropriate design for the intended sand blasting use, and, in the drawings, a circular casing or holder *a* is shown adapted to be fixed to a fitting on the pipe as for example by attachment of a welded-on flange *a*¹ indicated at Fig. 4.

10 The outlet or delivery end of the nozzle is shown fitted at the delivery end with hard-wearing liner elements of abrasion resisting metal *b*. These may be varied as to shape but are shown as of octagonal shape in cross-section and six are indicated abutting one to another within the bore of the nozzle. When assembled in position in the nozzle body they can be held in place by screws *c*. To further sustain the elements *b* their outer ends may abut against a flange *c*¹ shown in dotted lines, Fig. 4. Such elements *b* provide a liner with hexagonal passage way, and when wear has taken place same can be turned about to present a fresh wearing surface to restore the contour of the forward passage way of the nozzle. It is obvious that as wear occurs of liner elements *b*, same can be taken out and re-shaped, then re-combined and set-up by the screws *c* to restore to an approximation of the original passage way, so that the wear resisting elements can be gradually used

20 up as far as possible. The operative faces of liner elements *b* can be rounded or struck to a curve as indicated by dotted lines at *b*² so as to present an approximate cylindrical bore if required.

25 As regards the rear or inlet end of the nozzle, the renewable liner elements therefor consist, in the illustration, of six tapered plates *d* with inclined longitudinal edges *d*¹ as clearly shown by Figs. 2 and 3. These are assembled or combined as shown by Figs. 1 and 4 and produce a tapered hexagonal passage way or inlet. The inner ends abut on the liner elements *b* and a screwed ring *d*² is shown to retain in place the outer ends of the liner element *d*. Screws *d*² act on the rear of the six tapered plates *d*. It is seen that the inner ends of the tapered plates *d* where they rest on

the elements *b* produce a mouth coinciding with that produced by the assembly of liner elements *b* when the latter are of the shape shown in full lines in Fig. 5. It will also be apparent that the shape and disposition of the liner elements *d* produce a tapering hexagonal inlet to the nozzle. The inclined liner elements *d* do not suffer to the same extent as liner elements *b*, but when serious wear of a liner element *d* occurs same can be re-conditioned and replaced, or merely replaced.

In the modified structure shown by Figs. 7 to 10 the nozzle body *A* is rectangular in shape and the outlet or delivery section consists of two rectangular plates *e*, said plates *e* being of wear resisting metal and these may be brazed to backing plates *e*¹. The plates *e* (backed-up by the plates *e*¹) being renewable or changeable elements are held in relatively spaced position by screws *e*² which may engage the plates *e*¹ as indicated by dotted lines (see Fig. 10). The plates *e*, *e*¹ can be re-ground and adjusted or set-up as wear of liner elements *e* takes place. To maintain the spaced distance between plates *e*, *e*¹ hard-wearing renewable or changeable spacers *e*³ brazed to metal backing-up pieces *e*⁴ are shown, screws *e*⁵ being used to hold the spacers *e*³ in position, and such screws preferably engage with the backing-up pieces *e*⁴ for holding and adjustment purposes, see for example Fig. 10. This arrangement of liner elements *e*, *e*³ constitutes the forward or outlet part of the nozzle which it will be seen is slot shape.

The inlet end of the nozzle *A* consists of rectangular pieces or liner elements of wear resisting metal *g* with which are combined wedge-shaped rectangular backing-up plates *g*¹ advantageously brazed to said wear resisting metal pieces *g*. Said plates *g*, *g*¹ are held in place by pieces *g*² which screws may engage the plates *g*¹ as indicated by the dotted lines Figs. 7 and 8. By actuation of the screws *g*², and variation in the thickness of the liner elements *e*³ the width of the outlet slot and the size of the tapered inlet chamber *g*^x can be regulated. To close-up the ends of the tapered inlet chamber *g*^x, rectangular plates *h*, *h*¹ are used, the plate *h* being of wear resisting metal brazed to the backing-up plate *h*¹. The plates *h*, *h*¹ are held in position by screws *h*² which may engage plates *h*¹ as indicated by dotted lines Fig. 7. The lower forward part of each wear resisting plate *h* sits over the top part of each liner element *e*³ which regulate the width of the outlet slot, see Fig. 9.

The use of backing-up plates brazed to the wear resisting elements or parts are an advantage when used along with screws permitting of easier adjustment and ensuring better support of the wear resisting elements.

The body of the nozzle *A* (Figs. 7 to 10) is shown with a flange *A*¹ for securing to the attachment in connection with the supply pipe.

In Fig. 11 there is indicated an arrangement of wear resisting elements *B* shown as of hexagonal shape and capable of being re-ground or re-arranged to use-up the liner elements or to present fresh wearing faces, and screws *c* may be used to effect setting-up and fixing liner elements *B* arranged to produce an octagonal passage way capable of combining with renewable hard wearing metal plates or liners forming a tapered inlet compartment, said liner elements producing an octagonal outlet passage way in similar manner to what is described with reference to Figs. 1 to 4.

The spaces around the interchangeable re-face-

able or adjustable hard metal liner elements and bounded by the nozzle walls may be filled-up by running in lead to preclude easy passage of air due to the faces of the renewable re-faceable or interchangeable liner elements not being properly ground.

I declare that what I claim is:

1. A sand blasting nozzle comprising a body portion with rearward and forward insertable liner elements of wear resisting metal or alloy, the rearward elements adapted to combine in manner to permit same to be re-conditioned or changed as requisite on wear taking place, means to fix and adjust said removable elements, and forward wear resisting liner elements capable of being removed and re-ground or re-disposed and combined to provide fresh wearing surfaces, and means to fix and adjust said forward wear resisting elements in the body portion of the nozzle, all as described and shown with reference to Figs. 1 to 6.

2. A sand blasting nozzle comprising a body portion with rearward and forward insertable liner elements of wear resisting metal or alloy, the rearward elements adapted to combine and produce a tapered inlet, means to adjust and fix said elements, and forward insertable elements producing a slot-like outlet, means to hold and adjust said elements, all said liner elements being adaptable to be taken out and re-ground to present fresh faces and capable of being re-introduced, adjusted and fixed in the body portion of the nozzle, so that the nozzle is restored to the original inner contour as described and shown with reference to Figs. 7 to 10.

3. A sand blasting nozzle as claimed in claim 1, wherein the forward insertable liner elements of wear resisting metal or alloy capable of being turned and if necessary re-ground to produce fresh wearing surfaces are of hexagonal cross-section, said liner elements adapted to be combined and fixed in the fore part of the nozzle so as to produce an octagonal passage-way, as described herein with particular reference to Fig. 11.

4. A sand blasting nozzle having an exterior body portion which is a single entity, said body portion adapted to receive and be fitted with rearward and forward adjustable and fixable longitudinal abutting liner elements of wear resisting metal or alloy, which elements provide a complete interior to the nozzle to produce a built-up tapering rear nozzle compartment of abutting elements and a forward nozzle compartment of abutting elements, the aforesaid rearward liner elements in the rear compartment adapted to be taken out and re-ground or renewed and re-assembled, screw devices to fix same, the liner elements in the forward compartment being adapted to be reversed or inverted, ground or renewed as may be requisite, screws to fix said liner elements in the forward compartment, all whereby re-ground or fresh liner surfaces can be brought into use to produce a restored or new interior to the rear compartment of the nozzle, and freshly disposed or changed faces for the liner elements of the forward compartment, all so that a re-constituted or fresh cross-sectional area of the liner elements is obtained for the forward compartment approximating to the original bore or outlet of the nozzle, in manner described herein.

5. A sand blasting nozzle comprising an enveloping holder, combining machined liner elements fitted in the rear of said holder and capable of being redressed and replaceable or exchangeable, said liner elements shaped and ar-

ranged to produce a tapered rear compartment in the holder, screws to fix and adjust said liner elements, a forward compartment in said holder, and longitudinal multi-sided liner elements disposed in said forward compartment adapted to abut as to their sides and to combine one with another to produce a bore or passage way, said

5 multi-sided liner elements adapted to be dealt with and turned to bring fresh wearing surfaces into use to restore the original bore, and screws to adjust and fix said multi-sided liner elements in operable position in the forward part of the holder.

CHARLES DAVIES SPENLE.
